Attorney

UNITED STATES PATENT OFFICE.

CHARLES R. HOLCOMB, OF CHICAGO, ILLINOIS.

LEGGING.

Application filed August 1, 1927. Serial No. 209,659.

My invention relates to leggings intended for use in foundries and the like for the purpose of protecting the legs and feet of molders during exposure to molten metal 5 and intense heat; the invention contemplat- ing fastening means which will enable the legging to be easily applied and at the same time enable it to be quickly removed when occasion requires.

10 The main portion of the legging consists of suitable flexible material or fabric of more or less fire resisting quality, such as asbestos cloth or fire-proofed duck, provided with fastening means of such type that sag- 15 ging or undue wrinkling of the legging is prevented and the use of elaborate steel frames throughout the major portion of the legging obviated.

The advantages of my invention will be 20 readily apparent from the detailed description of the accompanying drawing, wherein—

Figure 1 is a perspective view of my im- 25 proved legging shown applied to a leg.

25 Figure 2 is a side elevation of the legging with intermediate portions broken away; the legging being shown in closed condition.

Figure 3 is a perspective view of the lower 30 part of the legging, the upper portion being broken away, and illustrating the fastening means at the bottom of the legging as em- 35 ployed in Figure 2.

Figure 4 is a similar view illustrating a 40 modification of the lower fastening means.

Figure 5 is a similar view of the lower 45 end of the legging showing another modified form of the fastening means for the lower end of the legging.

Figure 6 is a detail view, in perspective, of 50 another modification of bottom fastening means.

The legging is made of suitable flexible 55 material adapted to yield more or less to the curvatures and movements of the leg, be- 60 ing preferably made of sheet of fire-proofed duck to constitute the main body portion 10 cut to fit about the leg below the knee and to permit the two vertical sides to lap each other when applied, in order to completely 65 encase the lower part of the leg as shown in 70 Figure 1; the main body portion being pref- 75 erably cut from a single sheet of material.

The portion of the legging adapted to ex- 80 tend about the front part of the leg may be 85 provided with one or more strips of suitable

stiffening material, preferably of fibre, se- 90 cured on the inner side and extending verti- cally as shown in dotted lines at 11.

My improved legging is designed to ob- 95 viate the necessity for use of elaborate steel 60 reenforcing frames throughout the legging, except in one of the sides, where the ma- 70 terial is folded back upon itself as shown at 12 in Figure 3 and secured in place prefer- 75 ably by means of stitching as at 13, in order 80 to provide a pocket for the vertically dis- 85 posed reenforcing metallic stay 14 as shown in dotted lines in Figures 1 and 2. This 90 metallic stay is preferably arranged in the 95 side which is adapted to overlap the other 70 side 15 which may be termed the lapped or 100 inner side. The reenforcing stay 14 is also 105 secured in place by rivets which hold the 110 top and bottom fastening elements of the 115 legging.

The means for fastening the top of the 120 legging preferably consists of a snap-buckle 16, secured to the end of an adjust- 125 able strap 17; with the tongue of the 130 snap-buckle 16 inserted through an opening 18 in a finger grasping portion or tab 19 of 135 flexible material such as leather. It is ap- 140 parent that the fastening means may be 145 quickly released by pulling the free end of 150 the tab 19 away from the legging thereby 155 forcing the snap-buckle into open position.

My present invention involves a secure 160 and at the same time quickly released fasten- 165 ing means for the bottom of the legging 170 which consists in providing the underlap- 175 ping or inner side 15 of the legging at a 180 point preferably slightly removed from the 185 lower edge and on the outer surface with a 190 metallic strip 20 arranged vertically, with 195 the upper end rigidly secured to the legging, 200 as for example by rivets 21 so as to prevent 205 lateral movement; while the free end of the 210 strip 20 is bent upwardly into hook-form 215 to provide the upstanding tongue 22, spaced 220 slightly from the attached portion of the 225 strip.

The inside face of the other side of the 230 legging provided with the stay 14, namely 235 the side which overlaps side 15, is provided 240 with a horizontally disposed strip of sheet 245 metal 23, having intermediate portions bent 250 outwardly to provide a plurality of tongue 255 receiving loops or pockets 24. The ends of 260 the strip and the portion intermediate of 265 the pockets 24, are rigidly secured to the 270

legging, preferably by means of rivets 25; with one of said rivets 25 also extending through the reenforcing stay 14 which is also thereby secured in place. The strip 23 is secured to the outer lapping side at a point where it will normally be beneath the plane of the upper end of the tongue 22 of strip 20 when the legging is in place, so that the desired loop or pocket 24 may be slipped down over the tongue 22 as shown in Figure 2. This fastening means not only permits adjustment to various sized legs but also provides a secure fastening which at the same time can be quickly undone by an upward pull on the outer lapping side which carries the loop element.

In Figure 4, I illustrate a similar fastening except that the loop or tongue receiving pocket portion 26 is in the nature of a fabric strap or strip of leather rigidly secured to the legging, as for example by rivets 27; the strap being preferably of length to provide a number of tongue receiving pockets as shown so as to permit adjustment to suit the wearer. This strap 26, like strap 23, is positioned so as to normally be disposed beneath the top of the tongue 22 on the inner lapped side 15 of the legging; and the fastening is accomplished by slipping the desired loop or pocket of strap 26 over the tongue 22 like in the previously described construction.

Instead of employing separate strips of material for forming the tongue receiving portions, the overlapping side provided with stay 14, may be provided with one or more horizontally arranged slits as at 28 in Figure 5 cut in the legging and preferably reenforced by stitching or reenforcing material as shown at 29.

The inner lapped side 15 is shown provided with a vertically arranged strip 30 of stiff fibre or sheet metal; the lower end whereof is rigidly secured to the legging by means of rivets 31, or otherwise, to prevent lateral movement. The strip 30 above the riveted end is given a slightly outward bend so as to have the free upper end slightly removed from the side of the legging and extend substantially parallel with the lower attached end.

The slits 28, like the pocket or loop forming straps 23 and 26, are arranged so as to normally be disposed in a plane below the top of the tongue 30 when the legging is in place on the leg.

The stay 14 in all of the constructions disclosed, not only reenforces the outer or overlapping side and hence holds both sides against sagging by reason of the fastening means at top and bottom, but this stay enables the user to insert the pockets or tongue receiving portions over the tongues and obviates the necessity of reaching down to the bottom of the legging; release of the fasten-

ing means both at top and bottom of the legging being accomplished by proper manipulation at the top of the legging.

In Figure 6, I show another modification of the bottom fastening means, which involves the use of a strap 32 riveted or otherwise properly secured to the overlapping side of the legging as indicated at 33; the fastening means 33 being of a type and so arranged that the strap 32 will be maintained in the transverse position indicated on the inner side, adjacent to the bottom, of the outer lapping side of the legging. The strap 32 has one end provided with the ordinary buckle shown at 34, while the long end of the strap is provided with any suitable number of perforations as at 35 to receive the tongue of the buckle. It is apparent that the loop provided by the strap may be adjusted to the desired size in a direction transversely of the legging in order to snugly adjust the lower part of the legging to the wearer. The loop formed by the strap 32 is adapted to receive either the tongue 22 of the type of fastener shown in Figures 3 and 4, or the upper free end or tongue of the strip 30 shown in Figure 5.

The fastening means disclosed in Figure 6, like the other fastening means, permit the legging to be readily applied and also quickly removed, the removal being accomplished by grasping the tab 19 at the top and pulling outwardly from the leg thereby swinging the snap buckle tongue 16 into open position which allows it to slip out of the split or opening 18, while an upward pull on the portion of the legging provided with stay 14 will release the bottom fastening. The various fastening means for the bottom of the legging disclosed in the drawing permit adjustment of the legging to suit the wearer and thus obviate the necessity of manufacturing numerous leggings of various approximating sizes; and while the invention has been disclosed in what is believed to be the simplest and best embodiments, modifications may be made in certain details without, however, departing from the spirit of my invention.

What I claim is:

1. In a legging of the character described wherein one side is adapted to overlap the other, fastening means for the bottom of the legging comprising a stiff upwardly disposed tongue secured to one of said sides adjacent to the lower end thereof, and a tongue receiving portion on the other side adapted to be moved downwardly over said tongue.

2. A legging comprising a leg covering portion of protective material formed to permit the sides to lap each other, means for fastening the upper end of the legging, an upwardly disposed tongue secured at its lower end to one of said sides, and a tongue receiving portion on the other side in a plane

normally below the plane of the upper end of said tongue and adapted to be slipped downwardly over said tongue.

3. A legging comprising a leg covering portion of protective material formed to permit the sides to lap each other, means for fastening the upper end of the legging, an upwardly disposed tongue secured adjacent to the lower end of one of said sides, 10 means adjacent to the lower end of the other side normally below the plane of the upper end of said tongue adapted to receive said tongue, and a vertically disposed stay for reinforcing the side of the legging and to control the relation between said means and tongue.

4. In a legging wherein one side overlaps the other, a rigid upstanding tongue at the lower end of one side, and tongue receiving 20 means on the other lapping side, normally below the plane of the upper end of said tongue, adapted to permit adjustment to different leg thicknesses.

5. In a legging of the character described 25 wherein one side is adapted to overlap the

other, a rigid member secured to one of said sides adjacent to the lower end and provided with an upwardly disposed portion arranged in spaced relation with the side to constitute a tongue, the other side being provided with laterally spaced tongue receiving portions adjacent to the lower end of the legging normally in a plane below the upper end of said tongue, and a reenforcing stay in said last mentioned side whereby said portions may be slipped over said tongue. 30

6. In a legging of the character described wherein one side is adapted to overlap the other, a rigid member secured adjacent to the lower end of the inner lapped side and provided with an upwardly disposed tongue, the outer overlapping side being provided with transversely disposed tongue engaging means arranged in a plane normally below the upper end of said tongue, and a vertically disposed stay in one of said sides whereby the relation between the tongue and said means may be controlled. 40 45

CHARLES R. HOLCOMB.
